UNITED STATES PATENT OFFICE.

ANTOINE ARCHAMBAULT, OF NORTHAMPTON, MASSACHUSETTS.

WINDOW-SCREEN.

SPECIFICATION forming part of Letters Patent No. 408,786, dated August 13, 1889.

Application filed April 3, 1889. Serial No. 305,843. (No model.)

To all whom it may concern:

Be it known that I, ANTOINE ARCHAMBAULT, a subject of the Queen of Great Britain, residing at Northampton, in the county of Hampshire, and State of Massachusetts, have invented new and useful Improvements in Window-Screens, of which the following is a specification.

This invention relates to rolling window-screens, or to that class adapted to be by one end affixed to the sash and to be drawn up by and with the sash when the window is opened, thereby screening the window-opening to whatever extent of opening there may be, whether more or less, and to be withdrawn and disposed on a spring-reacting roller as the sash is lowered and the window-opening closed; and the invention consists in the construction and combination of the various parts, all substantially as will be hereinafter fully described, and specifically set forth in the claim.

In the accompanying drawings, Figure 1 is a front elevation of a window frame or easement and the screen mechanism of this invention applied thereto, with parts broken away for clearer illustration; and Fig. 2 is a vertical cross-sectional view of the same on line *xx*, Fig. 1.

In the drawings similar letters of reference indicate corresponding parts in all the views, and *A* represents the window-easement, the upper sash *B* sliding in the ways *b* therefor, and the lower sash *C* sliding in its ways *c*, and under or within the window-sill *a* a horizontally-extending chamber *D* is formed, in which is mounted a spring-reacting roller or reel *E*, on the periphery of which one end of the screen *F*, of textile netting or wire-gauze, is secured, which screen is of a width substantially equal to the width of the window. The upper end of said screen is provided with a horizontal rigid strip or bar *G*, to which it is attached.

The upper wall of the window-sill casing-chamber, in and about the plane of the sash, is formed with an opening *d* of sufficient width to permit the free passage therethrough of the screen, and the upper orifice of said opening is forwardly extended, as at *f*, forming a ledge *g*, on which the flange *h* of the strip *G* may rest, the main vertical portion of

said strip being adapted to lie within the said opening *d*, and at the time the sash is raised and the said strip not connected thereto the 55 said flange of the strip will close the opening, being prevented from following the screen through said opening by the flange and ledge engagement, and it will be seen by the formation of the said opening *d* with the laterally-extended orifice, and of the strip *G* with the flange, that when the said strip is in its lowermost position and resting by its flange on the ledge the top of the strip may lie flush with the upper surface of the window-sill, 65 and therefore the said strip constitutes no impediment to the close contacting of the sash with the window-sill and the complete closing of the window; and, moreover, when not desired to have the screen raised with and 70 by the window-sash, as is sometimes desirable while the window is raised, exposing the top of the window-sill, no aperture is left uncovered for the entrance of dust or moisture to the interior of the screen-inclosing casing, 75 the rest of the said flange on the ledge forming an effectual dust-guard. In accordance with this invention the said strip *G* is adapted to be connected to the lower edge of the sash by a catch device which is capable of easy 80 attachment and detachment, the construction and arrangement of which, fully shown in the drawings, is as follows:

The lower rail of the sash is recessed between its sides, as at *i*, said recess being open 85 at the lower edge of the sash, and in said recess is a transverse spindle *j*, bearing for rotation in the sash-rail, which spindle has at its end projecting beyond the outside of the sash-rail a handle-knob *k*, by which to conveniently turn it, and said spindle is also provided with a hooked arm *l*, fixed thereto and movable to swing with the spindle within the said recess.

m represents an angular arm on the upper 95 edge of the strip *G*, adapted, when the hooked arm *l* is properly swung into the upper part of the recess and the strip and sash-rail brought to contact, to protrude into the recess, and then on swinging the hooked arm *l* by 100 turning the knob to engage the angular arm *m* the strip will be connected to move with the sash.

The mounting of the spring-reacting roller

E for the screen within the chamber D of the casement is accomplished by supporting a shaft II immovably in the chamber D, on which the cylindrical roller is axially and 5 loosely mounted, a coiled spring *p* comprising a multiplicity of convolutions being wound about said shaft, one end of which is fixed to the shaft, as at *q*, while the other end thereof is attached to the head of the roller, as shown 10 at *r*.

With the screen-strip G through the catch devices above described connected to the sash, on raising the latter the screen will be unwound from its roller, and on lowering the 15 sash the roller will turn under the recoil of its spring and the screen will be correspondingly rewound.

What I claim as my invention is—

The combination, with a window-sill having a 20 easing thereunder and an opening *d*

therethrough, and the sash having in its lower rail a recess *i* within the thickness thereof and extended upwardly vertically from the lower edge thereof, the horizontal rotatable spindle projected across said recess and provided therein with the hooked arm *l*, said spindle being extended through and beyond the outer side of the sash-rail and there provided with a handle-knob, of the spring-reacting roller, and the flexible screen thereon projected through said casing-opening, and provided with the strip G, having the angular arm *m* adapted to project into said sash-recess *i* and be engaged by said hooked spindle-arm *l*, all substantially as shown, for the purpose set forth. 25 30 35

ANTOINE ARCHAMBAULT.
